UNITED STATES PATENT OFFICE.

GEORGE L. HARGEY, OF POTTSVILLE, PENNSYLVANIA.

PLUMBER'S TABLE AND VISE SUPPORT.

1,382,505.

Specification of Letters Patent. Patented June 21, 1921.

Application filed October 11, 1920. Serial No. 416,273.

To all whom it may concern:

Be it known that I, GEORGE L. HARGEY, a citizen of the United States, residing at Pottsville, in the county of Schuylkill and State of Pennsylvania, have invented certain new and useful Improvements in Plumbers' Table and Vise Supports, of which the following is a specification.

The object of this invention is, in general, 10 to provide a table and vise support adapted particularly for use by plumbers.

It is customary at present with plumbers to erect temporary supports with more or less makeshift materials, and this entails 15 considerable time, and the results are in many cases unsatisfactory. My invention is designed to provide a table and vise support, which is thoroughly practical, which is adjustable as to length, the parts of which are 20 readily assembled, and which may be quickly knocked down when the work of the plumber has been completed and it is desired to remove the structure.

A further object is to provide a device of 25 this character, the component parts of which are readily separable so that they may occupy a minimum amount of space when being carried from one place to another and when not in use.

30 A further object is to provide a device of this character in which the table supporting elements may be disposed in a vertical or horizontal position, while in either position of said supporting elements, the table or 35 vise platform may occupy a horizontal position.

With these objects in view and others appearing as the specification proceeds and the nature of the invention is more fully understood, the invention resides essentially in 40 two tubular members, means engaging the same for holding them in axial alinement and for moving them in reverse directions, a table adapted to support a plumber's vise, 45 and coöperating means carried by said table and one of said tubular members for supporting said table in a horizontal position, irrespective of whether said tubular members are disposed in a vertical or in a horizontal position.

The invention resides furthermore in the provision of cylindrical extension elements, which may be axially alined with said tubular members and which are used more particularly when the device is to be disposed 55 in a horizontal position, each of said tubu-

lar members and said extension elements carrying means for temporarily anchoring the device to stationary members.

The invention in its preferred form is 60 clearly disclosed in the accompanying drawings, forming part of my specification, and in which like reference characters denote corresponding parts throughout the several views. The several views of the drawings 65 may be briefly described as follows:

Figure 1 is a view in elevation of the device of my invention, shown as disposed in vertical position, certain parts being broken away;

Fig. 2 is a fragmentary view in elevation, partly in section, of the device, viewed from a position at right angles to that from which Fig. 1 is viewed;

Fig. 3 is a horizontal sectional view on 75 the line 3—3 of Fig. 1, looking in the direction of the arrows;

Fig. 4 is a detached detail view, in perspective, of one of the detachable anchoring 80 elements;

Fig. 5 is a view in side elevation of the device, shown as disposed in a horizontal position, and with the extension elements (shown in Figs. 1 and 2) removed;

Fig. 6 is a top plan view of the parts 85 shown in Fig. 5;

Fig. 7 is a transverse section on the line 7—7 of Fig. 5, looking in the direction of the arrows, and

Fig. 8 is a detached detail view, in perspective, of the other detachable anchoring 90 element.

Referring now in detail to the drawings:

1 and 2 designate two tubular members, the former being provided interiorly with 95 left-hand screw threads, and the latter with right-hand screw threads, or vice versa. Each of said members is provided, at one end thereof, with a series of anchoring teeth or projections 3, the teeth of each series being preferably equidistantly spaced. The bore of the member 1 is reduced at one end, as shown at 4, forming a socket, for a purpose presently appearing. The other member 2 is provided at one end with an enlarged 100 portion 5, which is interiorly threaded, as shown in Fig. 2, for a purpose presently appearing.

The member 2 is also provided, preferably at a point medially of the length thereof, 110 with a projection 6, shown in Figs. 5 and 7, for a purpose presently appearing.

A member 7 is provided for coupling the members 1 and 2 in axially alined relation and for moving them in reverse directions. Said member 7 is preferably tubular, as shown most clearly in Fig. 7, and for half of its length is provided exteriorly with right-hand threads, and for the other half with left-hand threads, as clearly shown in Fig. 2. The member 7 is, in use, screwed into the members 1 and 2, as shown in Figs. 1, 2, 5 and 6.

For conveniently rotating the member 7, suitable means may be provided, herein shown as a screw-collar 8 screwed onto the member 7, and held against independent rotation by set screws 9, or the like. The collar carries radial arms 10, constituting handles by which the collar, and with it the member 7, may be rotated, thereby longitudinally moving the members 1 and 2 in reverse directions.

11 designates a vise supporting table or platform, which is appropriately slotted, as shown at 12, for use in rigidly securing a plumber's vise A thereto. The table carries, centrally of its bottom, a tubular boss 13, in which is received the projection 6, when the members 1 and 2 are disposed in a horizontal position, as shown in Figs. 5 and 6. The table also carries a second tubular boss 14, which projects from one of the sides of the table, and is adapted to receive the projection 6, when the members 1 and 2 are disposed in a vertical position, as shown in Figs. 1 and 2. A cotter-pin 15 may pass through alined openings in the boss 14 and the projection 6 (see Figs. 1 and 7) for securing the table 11 against accidental displacement.

40 Receivable in the socket 5 of the member 2 is an extension element 16, preferably tubular, and provided with an exteriorly threaded end, which is screwed into the socket 5, as shown in Fig. 2.

45 A removable anchoring element is adapted to be positioned at the end of the extension element 16 opposite the screw-threaded end thereof, and this anchoring element preferably comprises a stem 17, which may be telescoped into the end of the member 16, and have a frictional retaining engagement with the wall thereof, or it may be threaded so as to be screwed into the end of the member 16, said end being, in this case, interiorly screw-threaded. Said anchoring member also comprises a disk 18 which is laterally carried by the stem 17, and is provided with teeth or prongs 19 adapted to bite into a stationary member 20, 50 such as the floor of a dwelling house, or the like.

An extension element is adapted to be positioned at one end of the member 1, and, preferably, this element is in two sections 65 21 and 22, the section 21 being a hollow

rod adapted to be received at one end thereof in the socket 4 of the member 1 and to telescope into the section 22. A collar 23 is carried by the section 21, and set screws 24 secure the collar in adjusted position on said section. One end of the section 22 is adapted to rest upon the collar 23, as shown in Fig. 1.

A detachable anchoring element 25, similar to the first-mentioned anchoring member, is adapted to be received in the upper end 75 of the section 22, as shown in Figs. 1 and 4.

It will be understood that while I have shown in Figs. 1 and 2 the use of the extension elements 16 and 21-22, when the device is placed in an upright or vertical position, yet it is to be understood that, if desired, said extension elements may be dispensed with when the tubular members 1 and 2 are disposed in an upright position. It will also be understood that while I have shown in Figs. 5 and 6, the members 1 and 2 without the extension elements, yet said extension elements may be used when the device is positioned in a horizontal position.

When it is desired to set up the parts of the device in operative position for use, the member 7 is engaged with the members 1 and 2, as shown, for instance, in Figs. 1 and 2; and if the extension elements 16 and 21-22 are used, the extension element 16 is 90 screwed into the coupling end 5 of the member 2, the extension section 21 is slipped into the socket 4 of the member 1 and telescoped into the extension section 22, the collar 23 being adjusted lengthwise of the section 21 95 and secured in adjusted position by the set screws 24. By then grasping the handles 10 and giving the collar 9 a rotary movement, the right and left-hand threaded member will be also rotated, thereby moving the 100 tubular members 1 and 2 in reverse directions and driving the prongs or teeth 19 of the anchoring elements into the stationary supports 20 and 26. The table 11 is now engaged with the projection 6 and the 110 cotter-pin 15 placed in position. The table 11 is now in position for use and a plumber's vise A may be secured on said table.

Having thus described my invention, what I claim to be new and desire to secure by Letters Patent is:

1. In a device of the character specified, two tubular members, a third member coupling the tubular members in axially alined relation and operable to move said tubular members in reverse directions, a table, and co-operating means carried by said table and one of said tubular members for supporting said table, with respect to said tubular members, in a horizontal position, irrespective 120 of whether said tubular members are disposed in a vertical or a horizontal position.

2. In a device of the character specified, two tubular members, a screw-threaded member coupling the tubular members in 130

- axially alined relation and operable to move said tubular members in reverse directions, a table, and coöperating means carried by said table and one of said tubular members 5 for supporting said table, with respect to said tubular members, in a horizontal position, irrespective of whether said tubular members are disposed in a vertical or a horizontal position.
- 10 3. In a device of the character specified, two tubular members, a third member coupling the tubular members in axially alined relation and operable to move said tubular members in reverse directions, a table, and coöperating means carried by said table and one of said tubular members for supporting said table, with respect to said tubular members, in a horizontal position, irrespective of whether said tubular members are disposed 15 in a vertical or a horizontal position, and a handle member carried by said third member for actuating the same.
4. In a device of the character specified, two tubular members, a third member coupling the tubular members in axially alined relation and operable to move said tubular members in reverse directions, a table, and coöperating means carried by said table and one of said tubular members for supporting 20 said table, with respect to said tubular members, in a horizontal position, irrespective of whether said tubular members are disposed in a vertical or a horizontal position, and a handle member carried by said third member for actuating the same.
- 25 30 35 40 45 50 55 60 65 70 75 80 85 90
5. In a device of the character specified, two tubular members, a third member coupling the tubular members in axially alined relation and operable to move said tubular members in reverse directions, a table, and coöperating means carried by said table and one of said tubular members for supporting said table, with respect to said tubular members, in a horizontal position, irrespective of whether said tubular members are disposed in a vertical or a horizontal position, and extension elements engageable with said tubular members.
6. In a device of the character specified, two tubular members, a third member coupling the tubular members in axially alined relation and operable to move said tubular members in reverse directions, a table, and coöperating means carried by said table and one of said tubular members for supporting said table, with respect to said tubular members, in a horizontal position, irrespective of whether said tubular members are disposed in a vertical or horizontal position, and anchoring teeth carried by each of said tubular members at one end thereof.
7. In a device of the character specified, two tubular members, a third member coupling the tubular members in axially alined relation and operable to move said tubular members in reverse directions, a table, and coöperating means carried by said table and one of said tubular members for supporting said table, with respect to said tubular members, in a horizontal position, irrespective of whether said tubular members are disposed in a vertical or horizontal position, and extension elements engageable with said tubular members.
8. In a device of the character specified, two tubular members, a third member coupling the tubular members in axially alined relation and operable to move said tubular members in reverse directions, a table, and coöperating means carried by said table and one of said tubular members for supporting said table, with respect to said tubular members, in a horizontal position, irrespective of whether said tubular members are disposed in a vertical or horizontal position, and extension elements engageable with said tubular members, and carrying anchoring means at the ends thereof.

GEORGE L. HARGEY.
